J. H. BRUNNER.

FEED CUTTER.

APPLICATION FILED JULY 26, 1920.

1,384,425.

Patented July 12, 1921.

Inventor
John H. Brunner

Cook & M-Carley Mfg.

UNITED STATES PATENT OFFICE.

JOHN H. BRUNNER, OF ALLENTON, MISSOURI.

FEED-CUTTER.

1,384,425.

Specification of Letters Patent. Patented July 12, 1921.

Application filed July 26, 1920. Serial No. 398,953.

To all whom it may concern:

Be it known that I, JOHN H. BRUNNER, a citizen of the United States of America, and a resident of Allenton, in the county of 5 St. Louis, in the State of Missouri, have invented certain new and useful Improvements in Feed-Cutters, of which the following is a full, clear, and exact description, reference being had to the accompanying 10 drawings, forming a part of this specification.

My invention relates to feed cutters in which beets, carrots, turnips, and other vegetables are cut up or shredded to make suitable stock feed. Generally stated, an object of my invention is to provide such a cutter which shall be simple, sturdy, efficient, and yet shall be inexpensive to construct. Another object of my invention is to 20 provide a cutter of this type which is easily operated and which can be quickly assembled and disassembled.

With the foregoing and other objects in view, the invention comprises the novel construction, combination and arrangement of parts hereinafter more specifically described and illustrated in the accompanying drawings wherein is shown the preferred embodiment of the invention. However, it is 30 to be understood that the invention comprehends changes, variations and modifications which come within the scope of the claims hereunto appended.

In the drawings, in which like numerals 35 indicate like parts in all the views,

Figure I is a top plan view of the mechanism.

Fig. II is a front elevation.

Fig. III is a vertical section taken approximately on the line III—III, Fig. II.

Fig. IV is an enlarged fragmentary vertical section of the cutter disk.

A designates a supporting table upon which is mounted the cutting mechanism. 45 1 designates a cutter disk, preferably made of sheet metal and having numerous perforations 2 therein. This disk is fixed to a shaft 3, which is adapted to rotate in bearings 4 mounted on the table A. An operating handle 5, by which the shaft and cutter disk may be manually driven, is connected to the outer end of the drive shaft 3, the operating handle having a hand-grip 5' thereon. The bearings 4 and the shaft 3 50 need not be of metal, for I have found that

good results are obtained when they are made of wood.

A feed trough 6 is mounted on the table and is inclined downwardly toward the cutter disk, the material to be cut being fed 60 against the cutter disk with one hand while the handle is rotated with the other hand.

The metal at only one side of each of the perforations 2 is bent outwardly from the plane of the inner surface 7 of the disk, so 65 as to provide short inclined teeth 9 adapted to shred or slice the material through the perforations.

As the beets or other vegetables are forced against the cutter, there is a pressure or 70 thrust exerted axially of the disk, tending to bend or bow the flexible disk outwardly about its axis. To overcome this bowing tendency, I have provided a thrust roller 8 adapted to bear against the outer surface of 75 the disk 1 at a point near the discharge end of the feed trough 6. This thrust roller 8 may be rubber tired if desired, so that it will not wear a groove in the disk 1, and is 80 freely mounted so as to be rotatable on a rod 10, which in turn is supported in notches 11' and 12' in supporting arms 11 and 12, said supporting arms being secured to said table and spaced substantially diametrically of 85 said disk. The ends of the rod 10 need not have a complete circumferential contact in the supporting arms 11 and 12, but should merely rest in the grooves therein, for there 90 will be no tendency for the rod to lift from the supports, as the thrust transmitted to 95 the rod 10 through the roller 8 will be downwardly upon the supports.

Another advantage of this type of support is that, in disassembling the cutter, no bolts or screws need be removed, for the rod and 95 roller may be simply lifted from its supports. To prevent the rod 10 from being displaced in operation, one of the ends, 13 is bent over the support 12.

A pair of semi-cylindrical drain guides 14 100 are mounted in alinement on the table, at opposite sides of the cutter disk, these drains converging toward each other at their lower ends and guiding the cut material dropped or thrown against them into any suitable 105 receptacle (not shown).

To confine any of the cut material thrown outwardly from the top of the disk by centrifugal force, a semi-circular guard 15 is provided, spaced a short distance around the 110

periphery of the disk, and secured at its ends to the table. A wear plate 16 may be interposed between the table and the cutter disk in order to prevent the teeth of the cutter disk from cutting the table.

To disassemble the device, the thrust roller and its rod are lifted off the supports, and the cutter disk and operating shaft are drawn out of the bearings 4. The disk may be easily cleaned with a wire brush after using and may be then put away until necessary to use it again, thus preventing the rusting and deterioration of the cutting edges.

15 I claim:

1. A machine of the character described comprising a shaft, a perforated cutter disk mounted on said shaft and secured thereto, supporting bearings at one end of said shaft, 20 an operating handle at the other end of said shaft, a rod extending across the face of said cutter disk adjacent thereto, a thrust roller rotatably mounted on said rod and adapted to bear against said perforated cutter disk, 25 and means whereby said rod is removably supported.

2. A machine of the character described comprising a shaft, a perforated cutter disk mounted on said shaft and secured thereto,

supporting bearings at one end of said shaft, 30 an operating handle at the other end of said shaft, a rod extending across the face of said cutter disk, a thrust roller rotatably mounted on said rod and bearing against said perforated cutter disk, and notched members 35 for removably supporting said rod.

3. A machine of the character described comprising a shaft, a perforated cutter disk mounted on said shaft and fixed thereto, supporting bearings at one end of said shaft, 40 an operating handle at the other end of said shaft, a rod extending diagonally across the face of said perforated cutter disk, a thrust roller rotatably mounted on said diagonal rod and bearing against said perforated cutter disk, said handle, thrust roller and diagonal rod being located at one side of said disk and said bearings being at the other side of the disk, and supporting members provided with notches open at the top in which said 45 diagonal rod is removably mounted, one end of said rod being bent downwardly to engage one of the notched members to retain said rod in said notched members. 50

In testimony that I claim the foregoing I 55 hereunto affix my signature.

JOHN H. BRUNNER.
